(57) **CLAIM**

We claim the ornamental design for a headwear cap with protective screen and neck sunshade flap, substantially as shown and described.

DESCRIPTION

FIG. 1 is a perspective view of a headwear cap with protective screen and neck sunshade flap;

FIG. 2 is a top plan view thereof;

FIG. 3 is a front elevational view thereof;

FIG. 4 is a rear elevational view thereof;

FIG. 5 is a right side elevational view thereof;

FIG. 6 is a right side elevational view thereof with the neck sunshade flap shown detached; and,

FIG. 7 is a rear elevational view thereof with the neck sunshade flap shown detached.

The broken lines showing a partial human figure represent environmental subject matter and form no part of the claimed design. The broken lines shown on the headwear cap with protective screen and neck sunshade flap are lines of stitching that are a part of the claimed design.
